ATTORNEY

UNITED STATES PATENT OFFICE.

HENRY SHELMON, OF VONTRESS, TEXAS.

BOTTLE CLOSURE.

Application filed July 16, 1920. Serial No. 396,684.

To all whom it may concern:

Be it known that I, HENRY SHELMON, a citizen of the United States, residing at Vontress, in the county of Haskell and State of Texas, have invented new and useful Improvements in Bottle Closures, of which the following is a specification.

This invention relates to improvements in bottle closures and has for an object the provision of a closure which may be easily removed from the bottle or applied thereto, to tightly close the bottle mouth.

Another object is the provision of a novel form of closure which is forced into engagement with a bottle mouth by means of a spring, so that a tight closure or seal is effected.

With the above and other objects in view, the invention includes the following novel features and details of construction, to be hereinafter more fully described, illustrated in the accompanying drawings and pointed out in the appended claim.

In the drawings:

25 Figure 1 is a fragmentary elevation of the neck of a bottle with the seal applied thereto, the latter being shown in section.

Figure 2 is an elevation of the seal removed.

30 Figure 3 is a sectional view similar to Figure 1 but showing the seal removed from the bottle.

Referring to the drawings in detail, wherein like characters of reference denote corresponding parts, the reference character 35 10 indicates the neck of a bottle which is provided with spaced annular flanges 11, the upper flange being formed in two sections which are spaced apart as shown at 12 40 the ends of one section being provided with vertical ribs 13 which extend downwardly from the upper edge of the lower flange so as to form diametrically opposite channels 15 whose entrances are through the 45 spaces 12.

The closure comprises a cap 16 having diametrically located legs 17 whose extremities are provided with inwardly extending lugs 18, the latter being designed to operate in the grooves 15 after passage through the 50 space 12. Positioned within the cap 16 is a disk 19 which is preferably formed of cork and interposed between this disk and the inner end of the wall of the cap is a spring 20 which acts to urge the disk toward the 55 open end of the cap.

In applying the closure, the lugs 18 are inserted within the grooves 15 by means of the interrupted portions 12 of the flanges, this action compressing the spring 20 so that 60 the disk 19 will fit tightly upon the mouth of the bottle. The cap is then rotated so that accidental disengagement will be prevented.

The invention is susceptible of various 65 changes in its form, proportions and minor details of construction and the right is herein reserved to make such changes as properly fall within the scope of the appended claim.

Having described the invention what is claimed is:-

The combination with a bottle, of a closure comprising a cap, diametrically oppositely arranged legs extending downwardly 75 from said cap, inwardly extending lugs formed on said legs, an annular flange surrounding the bottle neck, a sectional flange surrounding the neck above the annular flange, vertical ribs connecting the flanges 80 and extending from one end of each of the sectional flanges so as to form diametrically opposite channels for receiving the inwardly extending lugs, said lugs being adapted to engage the adjacent rib when the cap is in 85 locked position and spring means arranged in the top of the cap as and for the purpose specified.

In testimony whereof I affix my signature.

HENRY SHELMON.
